Primary Examiner — Cynthia M. Chin(74) *Attorney, Agent, or Firm* — ANDRUS
INTELLECTUAL PROPERTY LAW, LLP(57) **CLAIM**

The ornamental design for a railing for a marine vessel, as shown and described.

DESCRIPTION

FIG. 1 is a front perspective view of a railing for a marine vessel;

FIG. 2 is an isolated front perspective view thereof;

FIG. 3 is a rear perspective view thereof; and,

FIG. 4 is a front elevation view thereof.

The broken lines in the Figures illustrate portions of the railing for a marine vessel and marine vessel that form no part of the claimed design.

1 Claim, 4 Drawing Sheets(56)
